United States Patent Office.

ELLEN F. PRICE AND ELIZA A. MURPHY, OF NEW HAVEN, CONNECTICUT.

Design No. 3,142, dated July 28, 1868.

DESIGN FOR EMBOSSED PAPER, &c.

The Schedule referred to in these Letters Patent and making part of the same.

TO ALL WHOM IT MAY CONCERN:

Be it known that we, ELLEN F. PRICE and ELIZA A. MURPHY, of New Haven, in the county of New Haven, and State of Connecticut, have invented a new Design for Embossing Paper and Envelopes; and we do hereby declare the following, when taken in connection with the accompanying drawing, to be a full, clear, and exact description of the same, and which said drawing constitutes part of this specification, and represents an illustration of the design.

This invention relates to a design for embossing letter-paper and envelopes, and consists in embossing thereon the flower, and the sentiment of the same, as shown.

In the illustration given is a pansy or heart's-ease, with the sentiment of the same, "Think of me," also embossed beneath it.

What we claim as our invention, and desire to secure by Letters Patent, is—

The design, herein described and illustrated, for embossing letter-paper and envelopes.

ELLEN F. PRICE,
ELIZA A. MURPHY.
